LUBRICATING DEVICE

Verl E. McCoy, La Grange, Ill.

Application November 6, 1953, Serial No. 390,453

13 Claims. (Cl. 308—85)

My invention relates to lubricating devices and particularly to lubricating devices for axles of railroad cars and the like and has for one purpose the provision of a lubricating device which may be easily and quickly removed and installed.

Another purpose is to provide a lubricating device and support therefor which will be effective to apply the required amount of lubricant to an axle irrespective of the temperature of lubricant available to the lubricating device.

Another purpose is to provide a support for a lubricant device, which support shall be effective to cause the device to supply the proper amount of lubricant to an axle irrespective of the temperature of said lubricant.

Another purpose is to provide a seal for a rotating shaft or axle.

Another purpose is to provide a lubricating device having a member thereon adapted to prevent injury to said lubricating device during the use thereof.

Other purposes will appear from time to time throughout the specification and claims.

My invention is illustrated more or less diagrammatically in the accompanying drawings, wherein:

Figure 1 is a side view, in partial cross section of the device installed in a railroad junction box;

Figure 2 is a top view of the lubricating device and support therefor;

Figure 3 is an end view, in partial cross section, of the device illustrated in Figure 2 and on an enlarged scale;

Figure 4 is a view taken on a line 4—4 of Figure 3; and

Figure 5 is a detail view, on a reduced scale of the shaft seal illustrated in cross section in the right hand portion of Figure 1.

Like parts are indicated by like characters throughout the specification and drawings.

Referring now to the structure illustrated in the accompanying drawings:

Indicated generally at 1 is a journal box of a railway car. It will be understood that my lubricating device may be utilized in a variety of structures in which a rotating member such as an axle, be lubricated. For purposes of illustration, however, the device is shown as applied to the lubrication of axles of railway cars.

Indicated at 2 is an axle to be lubricated, disposed within the journal box. Beneath the axle 2 is the lubricating device generally indicated at 3. As will be seen in Figure 1 the lubricating device is installed within the journal box 1 in such manner to insure that a portion of the device is held in pressure contact with a portion of the axle 2, the axle 2 being supported in no way by the lubricating device itself.

An axle bearing is indicated at 4. In the case of the railway journal box illustrated, the axle bearing 4 is held, as by the wedge 5, between the axle and the top wall of the box and bears downwardly upon an upper surface of the axle within the journal box 1. For a more detailed description of the lubricating device 3 itself, reference

2

may be had to my copending application Serial No. 322,503, filed November 25, 1952, for "Lubricating Device." It is sufficient herein to state that the device 3 is comprised of a housing 10, which, may be formed of two half-shell members 10a—10b, each of which has a peripheral trough or semispherical channel 11—12. When the two half-shell members are secured together, as by the bolt-and-nut connections 6—7, the troughs 11—12 are in registration with each other to form a peripheral race 13. Disposed within the race 13 is a plurality of roller members or balls 15. Adjacent the lower portion, considering the device in the position which it assumes when installed, is the aperture or apertures 16, through which the lubricant generally indicated at 20 in the bottom of the journal box 1, enters the device to be picked up by the balls 15 as they pass through the race portion having the apertures 16. A portion of an outer edge of the device and the race 13 is cut away as at 22 to an extent sufficient to permit a portion of each of the balls 15 to extend therethrough as each ball traverses the cut-away portion. This cut-away portion is of insufficient size and depth, however, to permit the escape of the balls 15 from the race 13 or the housing 10.

It will be understood that the lubricating device is held in operating position at a vertically inclined angle, as illustrated in Figure 1. The cut away portion 22 is held in alignment with the bottom portion of the axle 2 to permit those portions of the balls 15 extending through the cut away portion to contact the axle 2 and to be rotated through the race 13 in response to such contact upon rotation of the axle 2. It will be seen, as is set forth in greater detail in my copending application referred to above, that the balls, in moving through the race 13, pick up lubricant in the bottom portion thereof and transfer said lubricant to the axle as they traverse the cut away portion 22.

Many mechanisms, such as the railway truck axle and box car journal box, are subject to fluctuation, vibration and shifting of the relative position of the parts to be lubricated. Thus, the lubricating device must be yieldingly held in pressure contact with the axle or item to be lubricated and, if continuous lubrication is to be achieved the device must be so held throughout such shifting and vibration.

25 illustrates a support for the lubricating device 3. The support 25 may be formed of a leaf spring having a general curvature such as that illustrated in Figure 1. Adjacent one end of the leaf spring 25 is an aperture 26 through which the securing means 27, which may be a nut and bolt connection, penetrates to secure the lubricating device 3 thereto, as illustrated in Figures 1, 2, and 3. In order to provide flexibility the lubricating device 3 may be pivotally mounted on the securing means 27, as illustrated in Figure 1 generally at 28. Adjacent the opposite end of the leaf spring 25 is a second aperture 29 through which the securing means 30, which may be also a nut and bolt connection, penetrates to secure the support 25 to a generally fixed structure, such as the journal box 1, adjacent the item to be lubricated. While the drawings illustrate the support 25 as being secured to the journal box adjacent the outer lower lip thereof, and while I find this to be a particularly satisfactory arrangement, it will be realized that the device could be secured to other portions of other generally fixed structures near an item to be lubricated without departing from the nature and scope of my invention. The support 25 has the elbow or bent portion 31 arranged to permit the end thereof which carries the aperture 29 to lie along the flattened outer lower lip of the journal box 1.

While, as will be described in greater detail below, the support 25 might consist of a single strip of metal responsive to the temperature of the lubricant 20, I find it advantageous also to form the support 25 of two metal strips

as indicated in Figure 3 at 25a—25b, thus forming a bimetallic spring or support. In such structure, the two strips are placed back-to-back, so to speak, and since the coefficients of expansion and contraction of the two metals are different, a change in temperature of the lubricant causes a bending of the curve portion and a consequent increase or decrease in pressure of the device 3 against the axle 2.

As will be best seen in Figure 1 the support 25 is curved sufficiently to permit the curved intermediate portion to lie within the lower portion of the lubricant supply 20.

While the tension of the leaf spring support 25 and its measurements may vary, I find, for example, when the device 3 itself weighs about three and one-half pounds, the spring tension may be four and one-half to five pounds and it may measure about one-sixteenth inch by one and one-half inches in cross section.

The lubricating device is subject to substantial vibration and shifting. Thus it is possible for the lower portion thereof to contact the bottom wall 1a of the journal box 1 or the bottom wall of whatever container is supplied for the supply of lubricant such as the lubricant 20. Such contact would, of course, tend to injure the device 3. I therefore provide a bumper or protector 50 along the lowermost outer portion of the lubricating device 3. As will be seen from a view of Figure 3 the bumper 50, which may be composed of a material having the characteristics of rubber, may be located intermediate the groupings of apertures 16. Since the lubricating device is normally installed in a plane inclined to the vertical, the bumper 50 must rise upwardly along the outer circumference of the channel 13 a distance sufficient to insure that the bumper 50 will intervene between the device 3 and the floor 1a as shown at 51 in Figure 1.

Illustrated at 60 in Figure 1 is the aperture in one end of the railroad junction box 1 which is penetrated by the axle 2. 61 indicates a seal for said axle and said aperture, effective to prevent the loss of lubricant therebetween. The seal 61 may be formed of foam neoprene rubber and is proportioned to fit snugly between the vertical walls 1b, 1c which have the aperture 60 and constitute a channel and support for the seal 61. As indicated in Figure 5 the seal 61 may be unitary and may have a generally centrally located aperture 62 through which the axle 2 extends. The diameter of the aperture 62 will normally be slightly less than that portion of the axle 2 which cooperates with the seal, for example, the diameter 62 may be approximately one-half inch less in diameter when the item to be lubricated is a railroad car axle. The outer configuration of the seal 61 is arranged to conform in general overall design with that of the journal box 1, i. e., the seal 61 has a generally rounded bottom edge 63 and a squared upper portion 64. It will be realized that the seal 61 may be inserted downwardly into the channel formed by the walls 1b—1c before the axle 2 is allowed to penetrate the apertures 60 and the housing 1. Thereafter the axle 2 may be inserted through the aperture 60 in the journal box 1 and through the aperture 62 in the seal 61 to take the position illustrated in Figure 1.

It will be realized that whereas I have described and claimed a practical and operative device, nevertheless, many changes may be made in size, shape, number and disposition of the parts without departing from the spirit of my invention. I therefore wish my description and drawings to be taken as in a broad sense illustrative or diagrammatic rather than as limiting me to the specific showing herein.

The use and operation of my invention are as follows:

I provide a lubricating device which is effective to transfer lubricants from a supply thereof to a rotating item to be lubricated, such as the railroad car axle 2. Since the lubricant illustrated at 20 is effected by fluctuations in temperature, whereby the lubricant will become more stiff

at lower temperatures and will thin out at higher temperatures, means are required to vary the amount of lubricant transferred to the axle 2 in response to such changes in temperature of the lubricant. As set forth in my copending application above, the amount of lubricant transferred to the axle 2 will vary substantially in proportion to the pressure of the balls 15 upwardly against the axle 2 as they traverse the cut away portion 22 in the lubricating device 3. Varying said upward pressure of the balls 15 against the axle 2 causes a corresponding variance in the speed of the balls 15 through the race 13 and thus causes a varied amount of lubricant to be transferred to the axle 2 in any given period of time.

I therefore provide a support for the lubricant device 3, which support shall be itself responsive to changes in the temperature of the lubricant 20 to vary the pressure of the balls 15 against the axle 2 and thus to vary the amount of lubricant transfer per unit of time to the axle 2 in response to changes in the temperature of the lubricant. The support 25 is secured to the journal box 1 and is caused to lie substantially within the lubricant 20 in a generally curved path and to support the device 3 at a point adjacent the end of the support 25 opposite the end secured to the ends of the box 1. The support 25 takes the general form of a leaf spring or strip of metal. The curved portion of the support 25 is formed of metal or metals which in response to changes in temperature will tend to contract and expand, said contraction and expansion causing a greater or lesser curvature in the support 25. As the curvature is increased the balls 15 are pressed upwardly against the axle 2 at a greater contact pressure. Conversely as the curvature of the support 25 is lessened in response to changes in the temperature of lubricant 20 the pressure of the balls 15 against the axle 2 is decreased. Thus the support 25 is effective to supply a greater or lesser amount of lubricant to the axle 2 per unit of time as the temperature of the lubricant 20 varies.

I provide a lubricant device which carries secured thereto its own protective and supporting element, namely the rubber-like bumper 50 which is effective to protect those portions of the device likely to come into vibrating and shifting contact with portions of the housing surrounding the item to be lubricated. Since the bumper 50 is secured directly to the device 3 it cannot be separated therefrom as a result of the vibration and shifting to which the device is subjected.

I utilize a seal adapted to seal a housing and rotating shaft inserted thereinto, which seal may be slidably inserted into a seal-supporting channel such as that formed by the walls 1b, 1c of the journal box 1. Since the seal 61 is formed integrally of one piece no possibility of leakage between separate portions of a seal exists. Since the aperture 62 is formed in this unitary seal and has a diameter less than the axle portion to be sealed a very effective sealing contact is created between the seal and the axle portion. Since the seal is formed of foam neoprene rubber a close and effective sealing contact may be achieved with the axle 2 and continued rotation does not enlarge the aperture 62 to create leaks. Since the above-described seal forms no part of the present invention, no claim is made thereto.

I claim:

1. A lubricating device comprising, a box member, a housing in said box member, a race of balls in said housing, an opening in said housing in registration with said race of sufficient size to permit a portion of said balls to extend therethrough and apertures in said housing in registration with said race, a supply of lubricant in said box member and available to said housing apertures and means in said box member responsive to changes in temperature of said lubricant to vary the position of said housing within said box member.

2. A lubricating device comprising, a box member, a housing positioned within said box member, a race of

balls in said housing, an opening in said housing in registration with said race of sufficient size to permit a portion of said balls to extend therethrough and apertures in said housing in registration with said race, a supply of lubricant in said box member and available to said housing apertures and means in said box member responsive to changes in temperature of said lubricant to vary the position of said housing within said box member, and means for protecting a portion of said housing against injury including a bumper secured to the outer portion of said housing diametrically opposite from said housing opening.

3. In combination, a railroad car journal box, a railroad car truck axle extending within said box, said box being substantially larger in cross section than said axle, a housing positioned within said journal box between a wall thereof and said axle, a race of generally rounded members rotatably and movably mounted in said housing, an opening in said housing through which extends a portion of said rounded members, a supply of lubricant in said journal box and in contact with said housing, an aperture in said housing at the point of contact of said lubricant and in communication with said race, a support for said housing adapted to maintain a portion of said rounded members which extends through said opening yieldingly in pressure contact with said axle as said rounded members are forced to traverse said opening by rotation of the axle against said rounded members, said support comprising a metal strip secured at one end to said journal box and at the other end to said housing, said strip having a curved portion intermediate its ends and extending into said lubricant supply.

4. The structure of claim 3 wherein said support is formed of at least two metals having different coefficients of expansion and contraction in response to thermal changes.

5. A lubricating device, comprising, a box-like member, a supply of lubricant in said box-like member, means for transferring said lubricant from said supply to an item to be lubricated, and a support connected to said lubricant-transferring means and to said box-like member, said support including a bimetallic strip having a portion in contact with said lubricant supply.

6. In combination, a journal box having a railroad truck axle extending therewith, said box being substantially larger in cross section than said axle, a supply of lubricant in said journal box, means in said journal box for transferring said lubricant to said axle, and a support for said lubricant-transferring means including a bimetallic strip secured at one end to said journal box and at the other end to said lubricant-transferring means, a portion of said bimetallic strip intermediate said ends being immersed in said lubricant supply.

7. The structure of claim 6 wherein said lubricant-transferring means is pivoted to said bimetallic strip.

8. The structure of claim 6 wherein said bimetallic strip is secured at one end to the outer, lower lip portion of the journal box and wherein said bimetallic strip curves downwardly therefrom into the lubricant supply and thereafter curves upwardly out of said lubricant supply at an angle to the axis of said axle.

9. In combination in a lubricating system for railroad car journal boxes, a journal box having a railroad truck axle extending therewith, said box being substantially larger in cross section than said axle, a housing adapted to fit within said journal box between a wall of said journal box and said axle, a race of generally rounded members rotatably and movably mounted in said housing, an opening in said housing through which extends a portion of said rounded members, a supply of lubricant in said journal box and in contact with said housing, an

aperture in said housing at a point of contact of said lubricant and in communication with said race, a support for said housing adapted to maintain a portion of said rounded members which extends through said opening yieldingly in pressure contact with said axle as said rounded members are forced to traverse said opening by rotation of the axle against said rounded members, said support including a bimetallic strip secured at one end to said journal box and at the other to said housing.

10. In combination in a lubricating system for railroad car journal boxes, a journal box having a railroad truck axle extending therewith, said box being substantially larger in cross section than said axle, a housing adapted to fit within said journal box between a wall of said journal box and said axle, a race of generally rounded members rotatably and movably mounted in said housing, an opening in said housing through which extends a portion of said rounded members, a supply of lubricant in said journal box and in contact with said housing, an aperture in said housing at the point of contact of said lubricant and in communication with said race, a support for said housing adapted to maintain a portion of said rounded members which extends through said opening yieldingly in pressure contact with said axle as said rounded members are forced to traverse said opening by rotation of the axle against said rounded members, said support including a bimetallic strip secured at one end to said journal box and at the other end to said housing, said bi-metallic strip having a curved portion intermediate its ends and immersed in said lubricant supply.

11. In combination in a lubricating system for railroad car journal boxes, a journal box having a railroad truck axle extending therewith, said box being substantially larger in cross section than said axle, a housing adapted to fit within said journal box between a wall of said journal box and said axle, a race of generally rounded members rotatably and movably mounted in said housing, an opening in said housing through which extends a portion of said rounded members, a supply of lubricant in said journal box and in contact with said housing, an aperture in said housing at the point of contact of said lubricant and in communication with said race, a support for said housing adapted to maintain a portion of said rounded members which extends through said opening yieldingly in pressure contact with said axle as said rounded members are forced to traverse said opening by rotation of the axle against said rounded members, said support including a bi-metallic strip secured at one end to said journal box and at the other end to said housing, said bi-metallic strip having a curved portion intermediate its ends and immersed in said lubricant supply, and bumper means disposed between said housing and said journal box wall including a flexible pad secured to the lower portion of said housing.

12. The structure of claim 11 wherein said pad is composed of flexible material having the characteristics of rubber.

13. In combination, a rotating shaft, a supply of lubricant arranged adjacent said shaft, a container for said lubricant supply, means for transferring lubricant from said supply to said shaft, and means for varying the position of said lubricant-transfer means in relation to said shaft, including a support secured to said lubricant-transfer means and secured to said container, said support having a portion in contact with said lubricant supply and responsive to temperature changes therein.
